THOMAS HILL, OF NEW CENTREVILLE, WISCONSIN.

Letters Patent No. 73,604, dated January 21, 1868.

IMPROVED LATHING-MACHINE.

The Schedule referred to in these Letters Patent and making part of the same.

TO ALL WHOM IT MAY CONCERN:

Be it known that I, THOMAS HILL, of New Centreville, in the county of St. Croix, and State of Wisconsin, have invented a new and improved Device for Facilitating the Nailing of Laths to Joists or Walls; and I do hereby declare that the following is a full, clear, and exact description thereof, which will enable those skilled in the art to make and use the same, reference being had to the accompanying drawings, forming part of this specification.

The invention relates to a new and useful device for facilitating the nailing of laths to joists or walls, and it consists in a novel construction and arrangement of parts, as hereinafter fully shown and described, whereby a number of laths may be adjusted together and held in proper position, so that they may all be applied to the joists or walls at the same time, and nailed thereto. In the accompanying sheet of drawings—

Figure 1 is a side sectional view of my invention, taken in the line xx , fig. 2.

Figure 2, a plan or top view of the same.

Figure 3, a side sectional view of the same, taken in the line yy , fig. 2.

Figure 4, a section of a portion of the same, taken in the line zz , fig. 2.

Figure 5, a portion of an enlarged section of the invention, taken in the same line yy as fig. 3.

Figure 6, a section of a portion of the invention, taken in the line $x'x'$, fig. 3.

Figure 7, a section of fig. 5, taken in the line $y'y'$.

Similar letters of reference indicate corresponding parts.

A represents an upright stand, composed of two uprights $a a$, connected at their upper ends by a horizontal cross-piece, b . The bottoms of the uprights $a a$ have spurs $c c$ in them, to catch into the floor and prevent the stand A from casually moving.

B represents a rectangular frame, the legs $d d$ of which are provided with casters e , at their lower ends, to admit of said frame being shifted or moved laterally, the cross-bars $f f$ of said frame passing loosely through the stand A. On the upper surface of the cross-piece b , of the stand A, there is secured, longitudinally, a cleat, c , of T-form in its transverse section, as shown clearly in fig. 4, and on the top of the frame B there is fitted a horizontal sliding frame, C, having on each side of its rear part a rack, D, into which pinions E E and a shaft F gear, said shaft having a lever-frame, G $\times$, attached, by actuating which the frame C may be moved forward and backward, in the direction indicated by the arrows 1 and 2 in fig. 2, (see fig. 2.)

G G represent three bars, provided, each, at one end with a metal socket, H. The bottom of each socket H has a box, I, attached, and the boxes of all the sockets are fitted on a bar, J, each box having a spring, g, within it to press upon the bar, or upon a plate, h, which rests thereon, (see more particularly fig. 7.) The bars G, therefore, it will be seen, are all attached to the bar J, and each bar G has a longitudinal groove, i, made in it, extending its whole length, with a rod, j, fitted longitudinally in each groove, and passing at one end through the sockets H, and at the opposite ends through plates k, secured to the opposite ends of the bars, said rods j holding the sockets firmly on the ends of the bars. On these rods j there are fitted, loosely, slides l, between which spiral springs m are placed, said springs being also fitted loosely on the rods j, (see fig. 8.) In each bar G there is placed a metal slide, n, to which two rods o o are attached, said rods extending through the sockets G and connected at their outer ends by a bar, p, the outer surfaces of which are bevelled, as shown clearly in fig. 5. The upper rod o, of each bar G, has a notch, r, made it to catch over the upper edge of the hole in the end of the socket H, the upper ends being pressed down to cause the notches to thus catch, in consequence of the bevelled edge s of the bar t of frame C being pressed against the outer bevelled edges of the bars p, as said frame is forced forward by actuating the lever-frame G $\times$, and by this movement of the frame C the laths are clamped between the slides l, and retained or held between them in consequence of the upper rods o catching in the outer ends of the sockets H, as described.

In adjusting the lath between the slides l, the cleat c on cross-piece b of stand A serves as a guide for one end of the lath to bear against, and the opposite ends of the lath may be sawed off, if necessary, in order to obtain a proper length. The springs m serve to compensate for varying thickness of laths. When the laths are thus secured to the bars G, the lever-frame G $\times$ is raised or thrown up, and the bars G with laths attached, taken off from frame B, and placed against the joists or the wall or flooring-timbers of the ceiling, the bar J having

clamps I^x attached to grasp the joists or timbers, and hold the bars G and laths thereto while the latter are being nailed. These clamps may be constructed similar to tongs, as shown clearly in fig. 6. After the laths are nailed to the joists or flooring-timbers, the bar J of the bars G are pressed towards the latter, and plates t , which are attached to the plates h , are by this means made to press against the notched rods o , and disengage the same from the sockets H , and thereby liberate the bars from the laths. The clamps I^x being then disengaged from the joists or flooring-timbers, the bars G are removed therefrom, and applied to frame B , to be again filled or supplied with laths.

I claim as new, and desire to secure by Letters Patent—

1. The stand A , in combination with the sliding or adjustable frame B , when used in connection with bars G , in which laths are clamped or secured, and all arranged in the manner substantially as and for the purpose set forth.
2. The sliding or adjustable frame C , connected with the lever-frame G^x by the racks and pinions $D E$, when said parts are used in connection with the frame B , and the bars G , provided with the slides l , and arranged to operate in the manner substantially as and for the purpose specified.
3. The slides l and springs m , placed on the rods j , within the bars G , and arranged to operate in connection with the frame C , substantially as and for the purpose set forth.
4. The rods $o o$, arranged with the notch r , frame G , springs g , and the plates h and t , to operate in connection with the slides l of bars G , substantially in the manner as and for the purpose set forth.
5. The clamps I , applied to the bar J , in combination with the bars G and the slides l , which hold the laths, all arranged substantially as and for the purpose specified.

THOMAS HILL.
